UNITED STATES PATENT OFFICE.

ROBERT T. BOURN, OF TEMPLETON, MASSACHUSETTS.

POST-OFFICE FURNITURE.

1,152,274.

Specification of Letters Patent. Patented Aug. 31, 1915.

Application filed June 2, 1911. Serial No. 630,845.

To all whom it may concern:

Be it known that I, ROBERT T. BOURN, a citizen of the United States, residing at Templeton, county of Worcester, State of Massachusetts, have invented an Improvement in Post-Office Furniture, of which the following description, in connection with the accompanying drawing, is a specification, like characters on the drawing representing like parts.

This invention relates to post-office furniture and especially to so-called routing cases for letter carriers' desks. One type of these letter carrier desks which is now more or less commonly used comprises a table above which is a routing case provided with shelves for receiving the mail and wire partitions for the shelves. In some types of cases the wire partitions are secured to the back and the lower edges of the partitions are spaced a slight distance above the shelf. In using routing cases of this construction it is found that when a single letter is placed between any two partitions the letter, especially if a small one, is liable to slip down underneath one of the partitions and thereby be misplaced and also interfere more or less with the placing of the mail in the adjacent partitions.

One of the objects of my invention is to provide a novel form of partition which will prevent this from happening and will insure that every letter, card or other piece of mail is properly held in its own compartment.

Another object of the invention is to provide a routing case of this nature in which the partitions are provided with extensions on their upper sides which not only serve to hold the mail in proper vertical position, but which also serve as guiding extensions to assist the letter carrier in locating the proper compartment for the insertion of mail.

Other objects of my invention are to provide a routing case which is adapted to receive both letter mail, paper mail or large packages, and which is so arranged that the spaces for the paper mail and the letter mail for any section or block of the route have a definite position relative to each other whereby the sorting of the mail is greatly facilitated.

Another object of my invention is to provide a routing case of the above type with an extensible table top whereby the table

can be arranged for sorting either letter mail or paper and package mail, thus obviating the necessity of using a separate table for sorting the paper and package mail.

Other objects of my invention are to improve generally post-office furniture of this type, all as will be more fully hereinafter described and then pointed out in the appended claims.

Referring to the drawings wherein I have shown some embodiments of my invention, Figure 1 is a front view of a routing case embodying the invention; Fig. 2 is a vertical section on the line $x-x$, Fig. 1; Fig. 3 is a detail perspective view of a portion of the table top; Fig. 4 is a fragmentary perspective view of one end of a shelf; Fig. 5 is a section on the line $y-y$, Fig. 4; Fig. 6 is a sectional view of the partition for the upper shelves; Fig. 7 is a detail of the shelf back; Fig. 8 shows a modification.

I have shown generally at 1 a letter-carrier's table which may have any suitable or usual construction. Situated above the table is a routing case which is formed with the two uprights or side pieces 2 adapted to support a plurality of shelves 3 and 4. The shelves 3 are designed to receive letter mail and the shelves 4 are designed to receive paper or package mail. These shelves may be sustained in position in any suitable way, as, for instance, by being supported on cleats 5 which are screwed or otherwise secured to the uprights 2. The cleats 5 are preferably screwed in place so that the position thereof may be shifted to permit the shelves to be spaced any desired distance apart. The shelves 3 and 4 are all preferably removably sustained on the cleats so that any one shelf with its contents may be readily removed. The shelves 3 for the letter mail are divided into compartments by means of partitions 7 which are formed of wire and are sustained by the back 8 of each shelf. The shelf backs 8 may be integral with the shelves or may be made rigid with the uprights 2. In the latter case the partitions will be sustained independently from the shelves so that when the shelves are removed the mail thereon will be withdrawn from the partitions.

As stated above, the partitions 7 are made by bending wire into loops and securing the ends 9 and 10 of the wire loops in the backs 8 of the shelves.

A routing case with the partitions arranged in this way is illustrated in Patent No. 803,575, November 7, 1905. Where the partitions are as shown in said patent and a single letter or card is placed in the compartment between two adjacent partitions, the letter is very likely to slip sidewise on the shelf and slide underneath one of the partitions, especially if the letter is a small one, or if the letter is a large one, it may assume such an inclined position that the upper edge thereof will overhang the partition at the top. In either event the letter obstructs the adjacent compartment more or less, thus interfering with the insertion of mail thereinto.

As stated above one of the objects of my invention is to provide a form of partition which will prevent any piece of mail in any compartment from sliding underneath the partition into the adjacent compartment or from overhanging the partition sufficiently to interfere with the insertion of mail into the adjacent compartment. I accomplish this object by providing my partitions with downwardly-directed extensions on their lower sides which extend substantially to the shelf and thus prevent any mail from sliding under the partition and by also providing each partition on its upper side with an upwardly-directed extension which will prevent any piece of mail from overhanging the partition.

There are various constructions embodying my invention which might be employed. In Fig. 2 I have shown the downwardly-directed extensions on each partition as formed by bending the wire to form a loop or bight 12 which extends downwardly from the lower side 11 of the partition and which in practice will meet or substantially meet the shelf. This extension 12 may be placed anywhere in the length of the partition where it will accomplish the desired purpose. The upwardly-directed extensions may also be formed by bending the upper side 13 of the wire to form the loop or bight 14 which extends nearly to the next partition above. This upwardly-directed extension may be placed in any suitable position on the partition. In Fig. 2 I have shown one extension situated substantially centrally of the partition and on the shelf below I have shown the extension as situated at the front end of the partition. In either case these extensions prevent the upper edge of any large piece of mail from overhanging the partition to such an extent as to interfere with inserting mail into the adjacent partition. Similarly the downwardly-directed extensions 12 will prevent any piece of mail from sliding under the partition and thus interfering with the insertion of mail into the adjacent compartment. The advantage of having the upwardly-directed extension

14 situated substantially centrally of the partition is that such extension will co-operate with a letter or card of any length to prevent the latter from overhanging the partition and also that the upper front corner of any card or letter will project beyond the partition so that it can be easily grasped by the carrier in taking down the mail. Furthermore, this upwardly-directed extension 14 serves as an eye guide to assist the carrier in properly placing the mail in the compartment, for these extensions project above the ordinary letters or cards and make the division line between successive compartments clear and distinct. Where the extension is on the front end of the partition as shown on the lower shelf in Fig. 2 the eye guide feature of the extension is augmented.

As stated above the shelves 3 are removable. Each shelf is provided at its back edge with a letter stop 16 which projects above the surface of the shelf and against which the letters may be positioned. In order to permit the shelves to be removed without any interference between the letter stop and the downward extension 12 of the partition, I have mounted the partitions so that they are capable of vertical movement. While this vertical movement may be provided for in a variety of ways without departing from my invention, I have herein shown a construction by which the partitions may have a slight rocking movement. This is accomplished by connecting the backs 8 to the partitions so that they can swing or rock. To provide for this I have herein shown the backs 8 as carried in rocking heads or supports 17 which are pivoted or swiveled to the sides of the routing case. These heads may be channel shape open at one end, as shown in Fig. 7, so that the backs 8 may be dropped into the channels thereof, and each head is provided with a trunnion 18 which is journaled in a recess formed in the side piece 2. A suitable stop 190 is employed for limiting the rocking movement of the head. With this construction it will be readily seen that when any shelf is withdrawn the engagement of the back stop 16 with the extensions 17 of the partitions will merely swing the partitions upwardly to permit the back stop to pass out from under the extension, and similarly when the shelf is inserted into place the engagement of the back stop 16 with the extensions will swing the back 8 and partitions upwardly to permit the back stop to pass.

In sorting the mail it is an advantage to have the shelves arranged stair fashion, that is, with each shelf projecting slightly beyond the shelf above, as shown in Fig. 2. The reason for this is that with the shelves arranged as shown when a letter carrier throws a letter or card into a compartment

the shelf above will not interfere with the rocking motion of the letter over the edge of the shelf on which it is to be received.

In Fig. 8 I have shown a construction wherein provision is made for simultaneously moving the shelves 3 outwardly into their desired position. This is accomplished by pivoting the heads 17 to swinging members 19 that are pivoted at their upper ends to the side pieces 2 and by making each shelf back 8 so that it will engage the back of the shelf. With this construction when the swinging members 19 are swung forwardly, as may be done by grasping the partitions for the lower shelf and drawing forwardly thereon, all of the shelves will be moved forwardly while maintaining the desired position relative to each other. This construction has the advantage that the lower shelf can be projected a greater or less distance depending upon the tastes of the carrier who is using the desk.

The shelves 4 for the letter and package mail are also removably sustained. These shelves may be divided into compartments by partitions 21 which are preferably adjustably sustained by the shelf so that they may be placed at different distances apart. These partitions can conveniently be made of wire bent into U-shape with the ends of the wire set into apertures 22 formed in the shelf, and I will preferably make the partitions solid by filling in the space between the sides of the U with sheet metal 23 which may be soldered, brazed or otherwise secured to the wire. In addition to these partitions I may use skeleton partitions 24 which can conveniently be formed of wire bent into U-shape and inserted into apertures formed in the shelf. The partitions 21 can be placed sufficiently far apart so that the compartments between them will accommodate magazines, laid flat.

Each shelf is provided at its end with a rest or guard which also constitutes a handle by which the shelf can be carried when it is removed from the case. This handle or guard is shown in the form of a wire 25 bent into U-shape and the sides of which occupy grooves 26 formed in the ends of the shelf and the ends of which are bent laterally, as at 27, and occupy grooves 28 formed on the under side of the shelf. Each wire 25 may conveniently be formed at its end with an eye 29 through which a screw may be inserted, thus rigidly fastening the wire to the shelf. With this construction the wires are located at the extreme end of the shelf so that no space is lost between the wires and the uprights 2. This construction furthermore has sufficient strength so that the wires 25 can be safely used as handles for carrying the shelf when it is loaded with mail matter.

Each shelf will be provided with routing strips 28 as usual in devices of this character on which routing strips the letter-carrier's route is outlined. I propose to divide the shelves for the letter mail and the shelves for the paper and package mail into sections corresponding to sections or blocks on the letter-carrier's route and to arrange the space for the letter mail and the space for the package mail corresponding to any particular section or block so that they will have a definite position relative to each other. For instance, the spaces on the upper shelf 4 for the paper and package mail correspond to the same portion of the route as the upper shelf 3 for the letter mail, and, therefore, when a carrier has a letter and a paper both of which belong to the same address he will place the letter mail in the proper position on the proper shelf and the paper or package is placed in a corresponding position on the corresponding shelf. This block system arrangement for the two sets of shelves is of great advantage because it facilitates the sorting of the mail and also the delivery of the mail from the routing case at nights or on holidays.

Another feature of my invention relates to an extensible top for the table 1 by means of which sufficient room on the table may be provided for the sorting of the paper, package and other large mail. This top extension is formed by making the table top in two sections 30 and 31. The section 30 is fixed and the section 31 is a sliding section 100 which slides under the section 30 and can be drawn out therefrom as indicated in dotted lines Fig. 2. When it is drawn out a greatly increased table surface is provided without increasing the floor space which the table occupies. I have provided a felt strip 32 which is secured to the front of the top section 30 and which contacts with the extensible section 31 and which prevents letters or cards from slipping in between the two top sections 30 and 31. This felt strip is secured to the front edge of the section 30 by a clamping strip 34 which is held in place by screws 35. The table top extension 31 is provided with the arms or end pieces 36 so that when said top extension is drawn outwardly into the dotted line position Fig. 2 the arms 36 constitute extensions of the side 37 of the table. The felt strip 32 extends at each end beyond the clamping strip 34, and such extending portions act as buffers or cushions for the arms 36 when the top extension 31 is pushed inwardly. This top extension is provided with hooks or supports 38 which are adapted to support a basket or mail receptacle 39 such as is more or less commonly used in post-offices. Since this receptacle is supported by the table top extension 31, it will be obvious that when the table top is drawn outwardly the mail

receptacle 39 will be moved outwardly with it and will thus be always accessible. These mail receptacles are commonly used to receive mail from the "jug" or "distributing cases" and the carrier may sort the mail from the receptacle or may empty said receptacle onto the table.

Having fully described my invention, what I claim as new and desire to secure 10 by Letters Patent is:—

1. A routing case for letter carriers comprising shelves and partitions supported independently from the shelves and dividing each shelf into compartments, each partition having its lower edge spaced from the shelf and provided with a downwardly-directed extension to prevent letters from sliding under the partition.

2. In a routing case for letter-carriers, the combination with a plurality of shelves each provided with a shelf back, of partitions supported by each back and having the lower edge thereof spaced from the shelf, each partition being formed with a downwardly-directed extension to prevent letters from sliding laterally under the partition.

3. In a routing case, the combination with superposed shelves, of partitions dividing the shelves into compartments, each partition having at its upper edge near its front end an upwardly-directed letter-positioning extension which extends substantially to the shelf above and forms an eye guide to assist the letter carrier in distinguishing the different compartments from each other.

4. In a routing case, the combination with a plurality of shelves, each provided with a shelf back, of partitions supported by each back and having the lower edge thereof spaced from the shelf, each partition being formed with a downwardly-directed extension to prevent letters from sliding laterally under the partition and also being provided 45 with an upwardly-directed letter-positioning extension.

5. In a routing case for letter-carriers, the combination with a frame, of shelves removably sustained thereby and each provided 50 with a back stop, and partitions for the shelves movable vertically relative thereto.

6. In a routing case, the combination with a frame, of shelves removably sustained thereby, each shelf having a back stop, vertically-movable partitions for each shelf, each partition having a downwardly-directed extension.

7. In a routing case, the combination with a frame, of a plurality of shelves removably sustained thereby, each shelf having a back stop, a rocking shelf back for each shelf, and partitions sustained by each shelf back.

8. In post-office furniture, the combination with a table having a top made in two sections, one of which is fixed and the other 65 of which is extensible, said extensible section sliding under the fixed section and when in fully retracted position extending beyond the fixed section a considerable distance and forming therewith the normal 70 working top of the table, means to limit the rearward movement of the extensible section, and a routing case situated above the table.

9. In post-office furniture, the combination with a table, of a routing case sustained 75 above the table, said table having a fixed top section and an extensible top section 80 slidably mounted to move underneath the fixed section, and when in retracted position extending beyond the fixed section and forming therewith the working top of the table, and a felt strip secured to the front edge of the fixed section and engaging the extensible section to prevent letters from 85 slipping between the sections.

10. In a routing case, the combination with a plurality of shelves, of partitions therefor 90 each comprising a wire bent into substantially U-shape, and a filling piece filling the U portion of the wire the ends of the wire projecting below the lower edge of the filling piece.

11. In post-office furniture, the combination with a frame, of a plurality of shelves 95 detachably sustained thereby, each shelf having at its end a combined handle and end rest of sufficient strength to permit a loaded shelf to be supported therby.

12. In a routing case, the combination 100 with a frame, of shelves removably sustained thereby, each shelf having at its end a wire bent into U-shape, the sides of which occupy grooves in the ends of the shelf and the ends 105 of which are bent laterally underneath the shelf and are secured thereto.

In testimony whereof, I have signed my name to this specification, in the presence of two subscribing witnesses.

ROBERT T. BOURN.
